United States Patent

Des. 240,000
Patented May 25, 1976

240,000

FEEDING DISH

Richard E. Cone II, 249 Bowman Drive, Kent, Ohio
44240, and Robert A. Hasenstab, 1678 Groton Drive,
Hudson, Ohio 44236

Filed Jan. 20, 1975, Ser. No. 542,507

Term of patent 14 years

Int. Cl. D7—01

U.S. Cl. D7—24

FIG. 1

FIG. 2

FIG. 3

FIG. 4

FIG. 1 is a top plan view of a feeding dish showing our new design;

FIG. 2 is a side elevational view thereof as viewed from the bottom of FIG. 1;

FIG. 3 is a side elevational view thereof as viewed from the top of FIG. 1; and

FIG. 4 is a bottom plan view thereof.

We claim:

The ornamental design for a feeding dish, as shown.
